UNITED STATES PATENT OFFICE.

CY WARMAN, OF WASHINGTON, DISTRICT OF COLUMBIA.

BICYCLE-LOCK.

SPECIFICATION forming part of Letters Patent No. 578,125, dated March 2, 1897.

Application filed October 27, 1896. Serial No. 610,182. (No model.)

To all whom it may concern:

Be it known that I, CY WARMAN, a citizen of the United States, residing at Washington, in the District of Columbia, have invented 55 certain new and useful Improvements in Bicycle-Locks; and I do declare the following to be a full, clear, and exact description of the invention, such as will enable others skilled in the art to which it appertains to make and 60 use the same, reference being had to the accompanying drawings, and to the letters of reference marked thereon, which form a part of this specification.

This invention relates to certain new and 65 useful improvements in bicycle-locks of that class having a movable arm adapted to be thrown between two of the spokes of the wheel to lock the latter against revolution, requiring no key to lock it, but requiring a key to unlock it, the lock being designed to be permanently affixed to some part of the frame of the bicycle.

The present invention has for its objects, among others, to provide a simple and cheap 75 yet durable and effective lock of this character, composed of few parts and those readily assembled, compact, and positive in their action and having provision for preventing its being unlocked by the introduction of any 80 instrument other than the proper key. I employ two pawls mounted for opposite movement and a single spring acting upon both of the said pawls, one pawl being designed to hold the locking-arm in one position and the other to move into position to prevent the introduction of any implement to unlock the arm after it has been moved a portion of its 85 distance.

The whole mechanism occupies but little 90 space, and when not in use is not unsightly in its appearance, nor does it add materially to the weight to be carried.

Other objects and advantages of the invention will hereinafter appear, and the novel 95 features thereof will be specifically defined by the appended claims.

The invention is clearly illustrated in the accompanying drawings, which, with the letters of reference marked thereon, form a part 100 of this specification, and in which—

Figure 1 is a view showing the application of the invention, the rim and tire of the bi-

cycle being in cross-section and the face-plate of the lock removed, the locking-arm being shown in its normal position by full lines and 55 in its locked position by dotted lines. Fig. 2 is a view of the portion of the frame to which the lock is applied seen at right angles to Fig. 1. Fig. 3 is an enlarged view of the lock with the face-plate removed and a portion of 60 the locking-arm broken off. Fig. 4 is a section on the line 4 4 of Fig. 3, showing also a portion of the key.

Like letters of reference indicate like parts throughout the several views. 65

Referring now to the details of the drawings by letter, A designates the lock-case, which is shown in this instance as rectangular in form, open at the lower end, as seen at a, and having upon one side adjacent thereto 70 the opening a' for the working of the locking-arm. This case is designed to be secured to the desired part of the bicycle-frame in any suitable manner, as, for instance, by the ears or lugs B, made to engage the frame, as 75 shown, and held thereto by a bolt or analogous means C.

D is a portion of the frame of the bicycle, E the rim, F the tire, and G one of the spokes, all of well-known construction, and as the 80 present invention does not relate in any way to the bicycle to which the lock itself is attached a further showing or description thereof is not necessary.

H is the locking-arm. It is mounted for 85 pivotal movement on the stud b, projecting from the case, as shown, and this arm is formed with a notch h, for a purpose which will soon appear. The locking-arm is also provided with a depression I about the stud, as seen in 90 Figs. 1, 3, and 4, to receive the central portion of the key, and from this depression in line with the longitudinal center of the arm is the notch J, which extends through the arm, as seen best in Fig. 4. 95

K is a pawl or dog pivotally mounted at one end on the pin or stud L at the lower end of the case, and the free end of this pawl has a tapered portion k at right angles to the length thereof to engage in the notch J of the locking-arm H to hold the same in its locked position, as seen by full lines in Fig. 3.

M is an oppositely-extending pawl mounted on the stud or pin m at the upper end of the

case, and its free end terminates in close proximity to the free end of the pawl K, as shown. This pawl serves to engage the notch J in the locking-arm to prevent the movement of the latter after the pawl K has been moved out of the said notch by the introduction of a knife-blade or other implement in an attempt to pick the lock. The construction of the key is such that it holds this supplemental pawl out of the way until after the arm has been moved a sufficient distance to bring the said notch past the point where this supplemental pawl would act to engage in the same.

N is a flat spring arranged within the case 15 at the side thereof, as shown, and its ends act upon the two pawls simultaneously, as will be readily understood from Figs. 1 and 3.

P is the face-plate to the lock-case. It is secured in position by screws or other means 20 and is provided with the keyhole Q, which is practically two keyholes disposed at right angles to each other.

R is the key. It is formed with a lug or depending portion r, which is adapted to enter 25 the notch J in the locking-arm and to engage and move away therefrom the tapered portion k of the pawl K when it is desired to unlock the arm. The key is introduced in the horizontal keyhole and cannot be removed 30 until it comes coincident with the vertical keyhole. When the locking-arm is thrown into its locking position, (horizontal,) the notch h thereof is engaged by the lower end of the side wall A' of the case, as seen in Fig. 35 3, to limit the upward movement of the arm and stop the same in position to receive the tapered portion of the locking-pawl.

Should an attempt be made to pick the lock to unlock the same with anything but the 40 proper key, the tapered portion of the pawl K may be thrown out of its engagement with the notch J of the locking-arm, so that it may be moved slightly on its pivot, but as soon as it reaches the position indicated by dotted 45 lines in Fig. 3 the supplemental pawl M springs into the notch and holds the arm against further movement, and as this is disposed out of the plane of either of the keyholes it is evident that it will hold the arm 50 against any further movement until the said

pawl is thrown out of the notch by the introduction of the proper key.

Modifications in detail may be resorted to without departing from the spirit of the invention or sacrificing any of its advantages. 55 I may sometimes employ a spring for holding the arm so that it will not sway back and forth during the movements of the bicycle. In Figs. 1 and 3 I have shown such a spring S extending across an opening s in the case 60 and against which the locking-arm will bear in its normal position and thus be held against movement, yet readily turned by hand to bring it to a horizontal position when desired.

What is claimed as new is— 65

1. The combination with the case and the pivoted locking-arm, of the oppositely-disposed pivotally-mounted pawls adapted to engage a notch in said arm, as and for the purpose specified. 70

2. The combination with the pivoted locking-arm having a notch, of the pivoted pawl having a tapered portion, the independent pawl mounted with its free end in proximity to the said tapered portion, and a spring having 75 its opposite ends acting upon the two pawls, substantially as shown and described.

3. The lock composed of the case open at the bottom and upon one side, the locking-arm pivotally mounted within the case and having 80 a notch at its inner end and a notch upon its outer face, the two oppositely-extending independently-pivoted pawls, and the spring arranged within the case with its ends acting one upon each pawl in proximity to the pivot 85 thereof, substantially as and for the purpose specified.

4. The combination with the case having a face-plate with two keyholes at right angles to each other, and a pivoted locking-arm, of 90 a locking-pawl, a supplemental retaining-pawl, and a spring mounted to act simultaneously upon both of said pawls, as shown and described.

In testimony whereof I affix my signature 95 in presence of two witnesses.

CY WARMAN.
